UNITED STATES PATENT OFFICE

IRVIN H. RIEKE, OF AUBURN, INDIANA, ASSIGNOR TO RIEKE METAL PRODUCTS CORPORATION, A CORPORATION OF INDIANA

SEAL FOR BUNG FIXTURES

Application filed November 2, 1929. Serial No. 404,300.

This invention relates to improvements in seals for bung fixtures, the object thereof being to provide, in connection with the bung ring of a container, a seal for closing the inner end thereof so that withdrawal of the contents of the container through the bung opening without first breaking the seal is prevented. Another object is to provide a seal for a bung ring so initially formed that its 10 marginal edge becomes permanently secured in the clinched end of the bung ring when said ring is installed in the wall of a container.

These objects are accomplished by the construction illustrated in the accompanying drawing, in which:—

Fig. 1 is a vertical section showing a bung ring inserted in the bung opening made in the wall of the container, with the seal applied thereto, the ring and seal appearing in their initial forms preparatory to the operation by which they are clinched permanently in place;

Fig. 2 is a similar view showing the ring and seal clinched in place; and

Fig. 3 is a plan view of the seal in its initial form.

A preferred form of the invention, as shown in the drawing, is applicable to that 20 type of bung ring 1 that is "pressed in" to secure it fixedly in the wall 2 of a sheet metal container (not shown), which wall is perforated and shaped so that a tube 3 is formed about the orifice in the wall for the reception of the sleeve 4 of the ring. The sleeve is internally screw threaded part way from its upper end, while its lower end portion 4', initially extends downwardly into the container beyond the end of the tube 3.

The seal 5 is preferably made of thin sheet metal, and is of circular form, the marginal portion thereof having an annular groove 6 bounded internally by a wall 7, and externally by a wall 8 concentric therewith.

The seal thus formed is applied to the extending end 4' so that the lowermost terminal of the ring is disposed within the groove 6 between said walls 7 and 8. Pressure is then applied to the ring and said walls of the seal, by means of suitable dies (not shown),

so that the thin extending portion 4' of the ring and the wall 8 of the seal are clinched externally about the lower end of the tube 3 and thus permanently securing the ring and the seal in connection with the wall 2 of the 55 container as shown in Fig. 2.

The seal when thus secured in place closes the inner end of the ring and prevents tampering with the contents of the container until purposely cut away or broken to gain 60 entrance to the container through the ring. The seal thus disposed permits the ring to be closed by an ordinary bung (not shown) in the usual manner without being dislodged.

The container, equipped with the seal 65 above described, is filled through a separate opening (not shown) provided for the purpose, which is permanently sealed or closed in any well known manner after the container has been initially charged with the material to be shipped, and thus removal of the material from the container other than through the bung ring is prevented. The presence of the seal, unbroken, at the lower end of the bung ring, upon removal of the 70 bung, indicates to the receiver of the container that the content originally shipped 75 therein is genuine.

I claim:

1. A bung fixture and seal therefor comprising a container wall having an orifice and provided with a tube upon the inner side of the wall surrounding said orifice, a bung ring having a sleeve extending through said orifice and tube, and a breakable seal 80 closing the inner end of said ring, the lower end of said ring and the marginal portion of said seal being clinched together around the lower end of said tube whereby the sleeve, tube and seal are conjoined at the lower end 85 of the tube whereby to permit insertion and removal of a bung in said ring without disturbance of said seal.

2. In a bung fixture for a container, a container wall formed with an orifice and contiguous tube extending inwardly about said orifice, a bung ring having a sleeve extending axially through the tube, and a breakable seal, the lower end of said ring and the marginal portion of said seal being clinched 95 100

about the lower end of said tube with the marginal portion of said seal disposed between the clinched portion of the sleeve and exterior of the tube, whereby the ring, seal and tube are conjoined at the lower end of the tube.

In testimony whereof I affix my signature.

IRVIN H. RIEKE.
